(57) **CLAIM**

The ornamental design for a condiment container, as shown and described.

DESCRIPTION

FIG. 1 is a perspective view of the condiment container;
 FIG. 2 is a top view of the condiment container;
 FIG. 3 a bottom view of the condiment container;
 FIG. 4 is a front view of the condiment container, the left-side view being a mirror image thereof;
 FIG. 5 is a rear view of the condiment container; and,
 FIG. 6 is a right-side view of the condiment container; and,
 FIG. 7 is a left-side view of the condiment container.
 The broken line showing of structure is for illustrative purposes only, and forms no part of the claimed design.

1 Claim, 3 Drawing Sheets# US D682,710 S
